MANUFACTURE OF PILE FABRICS

Wolfgang Michaelis, Neubabelsberg, near
Potsdam, GermanyApplication March 30, 1931, Serial No. 526,374
In Germany May 10, 1930

8 Claims. (Cl. 139—405)

This invention relates to wire warp pile fabrics with back pattern woven through, in particular for the production of carpets and the like, which are very similar in appearance to real Oriental carpets. With the fabric, to which the invention refers, there are present in the fabric not only the pile warp threads forming the pattern at the moment but also the other pile warps lie as so-called dead pile warps between the upper and the 5 backing weft in the fabric.

With one known wire warp pile fabric of the kind mentioned, the pile warp threads forming the pattern are simply tied underneath the base warp by backing wefts. The disadvantage of the 10 said method of weaving consists, on the one hand, in the comparatively easy loosening of the pile threads from the fabric, and on the other hand, the back of the fabric, in spite of the back pattern woven through, has not the appearance 15 of the back of real Oriental carpets as the cross entanglement of the pile warp threads forming the pattern is wanting.

With another known process, by the aid of which wire warp pile fabrics with back patterns 20 woven through and dead pile warps lying in the fabric are produced, a twisting of the pile warp threads round the ground warp takes place. It is characteristic, however, of the last-mentioned process that all the pile warp threads, that is 25 therefore both the ones serving at the moment to form the pattern as well as the dead pile warp threads, lie permanently twisted in the weaving process. The treatment of the pile warp thread serving to form the pattern differs 30 from the treatment of the other pile warp threads simply in that the pile warp thread serving to form the pattern is lifted up, in order to place it over the wire. With this known process, the permanent twisting of all the pile warp threads 35 has the great disadvantage that the pile warp threads are heavily stressed. In carrying out the last-mentioned process, therefore, either material of great strength and consequently expensive, is necessary for the pile warp threads, or 40 the pile warp threads must consist of highly twisted material which has the disadvantage of forming an uneven pile. Furthermore, a considerably increased consumption of material is 45 connected with the process in question, which is to be attributed to the working in of the permanently twisted dead pile warp threads. Finally, 50 owing to the permanent twisting of all the pile warp threads, the faults taking place in weaving, in particular the formation of knots, are increased.

By means of the process according to the present invention, the disadvantages attaching to the known processes are avoided. The process according to the invention is characterized by a lesser consumption of material and a smaller stressing of the pile warp threads, and produces a strong close fabric with good pile formation in which the pile threads are so firmly tied in that they cannot practically be detached from the fabric. According to the invention, of the pile 10 warp threads lying untwisted in the fabric, the pile warp threads lifted at the moment to make the pattern, are carried to the back of the fabric and there interlaced round the ground warp in 15 half twist weave.

Owing to the fact that only the pile warp threads lifted up over the wires are twisted, while the other dead pile warp threads lie untwisted in the fabric, the pile warp material is greatly protected. Furthermore, with the process according 20 to the invention, less strongly twisted yarns which permit of a closer pile can be used. There is also a considerable saving of material attaching to the process according to the invention, as the dead pile warp threads lie in the fabric without 25 working in. The saving in material can also be increased with the process according to the invention by the firmer interlacing which is made possible by the twisting of only the pile warp threads forming the pattern. Furthermore, the 30 interlacing takes place preferably always only round one ground warp thread, which also effects a saving of material. As, furthermore, only the pile warp threads serving to form the pattern are carried to the back of the fabric, the possibility 35 of the occurrence of faults in weaving in consequence of knots and the like, is reduced. Finally, a considerable saving in power and time is effected in the process according to the invention. 40

The invention is more fully explained on the drawings by means of a number of examples of carrying it out.

Figs. 1 and 2 show a double weft wire warp pile 45 fabric according to the invention diagrammatically in longitudinal section and in plan.

Fig. 3 also shows a double weft wire warp pile fabric according to the invention with altered position of the top weft, diagrammatically in 50 longitudinal section.

Figs. 4 and 5 show diagrammatically in longitudinal section and in plan a triple weft wire warp pile fabric according to the invention, while

Figs. 6 and 7 also show a triple weft wire warp 55

pile fabric according to the invention with altered position of one bottom weft.

Fig. 8 shows in longitudinal section a fabric corresponding to that shown in Fig. 4 but having the upper weft introduced simultaneously with the wire.

Fig. 9 shows in longitudinal section a fabric corresponding to that shown in Fig. 6 but having the upper weft introduced with the wire.

10 Figs. 10 and 11 show in longitudinal section and in plan a fabric corresponding to that shown in Figs. 1 and 2 in which the wire is placed in the knot and the lower weft introduced into the loop.

15 Figs. 12 and 13 are similar views of a fabric corresponding to that shown in Figs. 4 and 5 modified in the same manner as Figs. 10 and 11.

20 Figs. 14 and 15 are similar views of a fabric corresponding to that shown in Figs. 6 and 7. In the figures, 1 indicates the ground warp. 2, 3, 4, 5, 6 are five pile warps which serve to form the pattern, and which consequently have the different colours necessary for the formation of the pattern. 7 indicates the binding warp.

25 The fabrics shown in Figs. 1 to 3 are double weft fabrics, 8 indicating the top weft, and 9 the lower weft, which are introduced with each working cycle. 10 indicates the wires over which the pile warp threads lifted up at any time in order to form the pattern, are laid.

The process for the production of the fabric according to Figs. 1 and 2 takes place in much the following manner:

30 The weft 8 is introduced under the binding warp, while the ground warp and all the pile warps are lowered. At the same time, or immediately afterwards, that thread of the pile warp, as for example the thread 6 which is to serve to form the pattern, is lowered by means 35 of the jacquard mechanism under the other pile warp threads 2, 3, 4, 5 and under the ground warp 1. The same thing can be attained by the pile warp threads 2, 3, 4 and 5, and the ground warp 1 being raised. The pile warp thread serving 40 to form the pattern is drawn away under the ground warp, and is brought twisted into the upper shed, so that the part a (see Fig. 2) is formed.

45 After the raising of the pile threads twisted at the side, a second weft thread 9 is introduced over the ground and binding warp, and under the partly twisted and partly untwisted pile warp threads. The members which have effected the 50 raising of the pile warp thread twisted round the ground warp then sink, so that this pile warp thread springs back. Finally, the previously 55 twisted pile warp thread is lifted up by means of jacquard cords into a straight direction (see part b) in order to be placed in the upper shed over the wire 10. In the bottom shed, on the other hand, 60 are the ground and binding warps, as also the so-called dead pile warp threads which do not take part in the formation of the pattern.

65 After the pile warp thread raised over the wire has been lowered, first the binding warp is again raised alone into the upper shed, and a fresh weft 8 is inserted. The twisting of the next pattern forming pile warp thread then begins, this 70 lying, after its lifting, twisted in the upper shed, whereupon the lower weft 9 is inserted. The pattern forming thread springs back and is finally laid over the wire. In this manner, the working cycle is continuously repeated.

75 In order to carry out the above described proc-

ess, a three-repeat weaving loom is generally necessary.

The fabric according to Fig. 3 differs from the fabric according to Figs. 1 and 2 simply in that the upper weft 8 is introduced at the same time as the wire 10, so that the upper weft 8 lies not only under the binding warp 7 but at the same time also under the pile warp thread raised over the wire 10. By introducing the upper weft 8 at the same time as the wire 10, it is possible to use 10 a double-repeat weaving loom. Apart from the introduction of the upper weft simultaneously with the wire, the process for making the fabric according to Fig. 3 is entirely the same as the above described process.

15 The fabric which is shown in Figs. 4 and 5 differs from the fabric according to Figs. 1 and 2 by the fact that between the pile warp thread serving to form the pattern, after it is lowered below the ground warp 1, and the ground warp, 20 a third weft 11 is introduced, by means of which the principal purpose in view is to bring the back pattern of the carpet fully into accord with the back pattern of real Oriental carpets. With the object of Figs. 4 and 5, the binding warp 7 is also 25 woven below the ground warp 1 by the weft thread 11. The binding warp 7 does not, however, need to be woven underneath the ground warp, but can be also interlaced in the manner shown from Figs. 1 and 3 by the lower weft 9, which lies above 30 the ground warp 1.

Apart from the introduction of the second lower weft 11 the process for the production of the fabric according to Figs. 4 and 5 is the same as that above described for the Figs. 1 and 2.

35 In Figs. 6 and 7 a triple weft fabric is also shown and there are also here two bottom wefts. The one bottom weft 9 has the same position and the same function as the bottom weft 9 according to Figs. 1 and 2, while the second bottom weft 40 12, after the introduction of the weft thread 9 is introduced above the ground warp and the pile warp thread serving to form the pattern, and underneath the binding warp and the dead pile 45 warp threads. The weft thread 12 has the object of making the fabric still thicker. Apart from the introduction of the weft thread 12, the process of production is the same with the object of Figs. 6 to 7, as with the object of Figs. 1 and 2.

50 In the production of the triple weft fabrics according to Figs. 4 to 7, four-repeat looms are to be used. With the fabrics according to Figs. 4 to 7, the upper weft 8 can, in the same way as has been explained in the case of Fig. 3, be introduced simultaneously with the wire 10 (Figs. 55 8 and 9). In this case, only three repeat looms are necessary for the production of the fabric according to Figs. 4 to 7.

55 In order to obtain a similarity to real Persian carpets, in the matter of the fringe making, the ground warp 1 may be allowed to project from the woven goods so that it can be used for the knotting of the fringe.

60 The wire can also be placed in the knot a (see Figs. 2, 5 and 7) and in place of this the lower weft 9 be introduced above the ground warp in the part b (Figs. 10 to 15).

I claim:

65 1. A wire warp pile fabric having a plurality of ground warp threads, each of said ground warp threads having associated therewith a plurality of pile warp threads, and weft threads, said pile warp threads serving to form patterns, each of said pile warp threads having at selected locations a portion extending above the face of the 70

75

fabric to form the pattern and an adjacent portion bent around the ground warp thread with which said pile warp thread is associated and forming a loop on the opposite side of said ground 5 warp thread from said pattern forming portion, and a weft extending through said loop, the portions of the other pile warp threads associated with such ground warp thread adjacent said pattern forming portion and bent portion lying unbent in the fabric.

2. A wire warp pile fabric having a plurality of ground warp threads, each of said ground warp threads having associated therewith a plurality of pile warp threads, and weft threads, 15 said pile warp threads serving to form patterns, each of said pile warp threads having at selected locations a portion extending above the face of the fabric forming a loop and an adjacent portion bent around the ground warp thread with 20 which said pile warp thread is associated and engaging the lower side thereof and forming a loop on the opposite side of said ground warp thread from said pattern forming portion, and a weft thread extending through said second loop, 25 the portions of the other pile warp threads associated with such ground warp thread adjacent said loop and bent portion lying unbent in the fabric, said first loop being on the same side of the ground warp thread as said unbent portions.

3. A wire warp pile fabric having a plurality of ground warp threads, each of said ground warp threads having associated therewith, a plurality of pile warp threads, and weft threads, said pile warp threads serving to form patterns, each 35 of said pile warp threads having at selected locations a portion extending above the face of the fabric to form the pattern and an adjacent portion bent around the ground warp thread with which said pile warp thread is associated and 40 engaging the lower side thereof and forming a loop on the opposite side of said ground warp thread from said pattern forming portion, the portions of the other pile warp threads associated with such ground warp thread adjacent said pattern 45 forming portion and bent portion lying unbent in the fabric, said weft threads comprising an upper weft thread and a lower weft thread located between said ground warp thread and said pile warp threads, said lower weft thread extending through said second loop.

4. A wire warp pile fabric having a plurality of ground warp threads, each of said ground warp threads having associated therewith a plurality of pile warp threads, and weft threads, 55 said pile warp threads serving to form patterns each of said pile warp threads having at selected locations a portion extending above the face of the fabric to form the pattern and an adjacent portion bent around the ground warp thread with which said pile warp thread is associated and engaging the lower side thereof and forming a loop on the opposite side of said ground warp thread from said pattern forming portion,

the portions of the other pile warp threads associated with such ground warp thread adjacent said pattern forming portion and bent portion lying unbent in the fabric, said weft threads comprising an upper weft thread, an intermediate weft thread between said ground warp thread and said pile warp threads and extending through said loop, and a lower weft thread lying below the ground warp thread, said bent portion of said pattern forming warp thread 10 engaging said lower weft thread and binding the same against said ground warp thread.

5. The process for producing wire warp pile fabrics having ground warp threads, a plurality of pile warp threads associated with each ground 15 warp thread, and weft threads, which comprises carrying that one of the pile warp threads which forms the pattern at any point to the back of the fabric and bending the same around the ground warp thread, while leaving the adjacent 20 portions of the remaining pile warp threads unbent in the fabric, forming a loop in an adjacent portion of said pattern forming thread on the opposite side of the ground warp thread from the pattern forming portion, inserting a 25 weft thread through said loop, and repeating said steps for each of said pile warp threads selectively to form a pattern.

6. In a process as claimed in claim 5, the step of inserting a weft thread below said ground 30 warp thread and between said ground warp thread and that portion of the pattern forming pile warp thread which is bent around the ground warp thread.

7. In a process as claimed in claim 5, the step 35 of inserting a weft thread between said pile warp threads and said ground warp thread at a point outside the said loop.

8. A wire warp pile fabric having a plurality of ground warp threads, each of said ground 40 warp threads having associated therewith a plurality of pile warp threads, and weft threads, said pile warp threads serving to form patterns, each of said pile warp threads having at selected locations a portion extending above the face of the fabric to form the pattern and an adjacent 45 portion bent around the ground warp thread with which said pile warp thread is associated and engaging the lower side thereof and forming a loop on the opposite side of said ground warp 50 thread from said pattern forming portion, the portions of the other pile warp threads associated with such ground warp thread adjacent said pattern forming portion and bent portion lying unbent in the fabric, said weft threads comprising an upper weft thread, a lower weft 55 thread located between said ground warp threads and said pile warp threads and extending through said loop, and a third weft thread lying between said pile warp threads and said ground warp thread at a point outside said loop.

WOLFGANG MICHAELIS.
